Patented Nov. 11, 1919.

UNITED STATES PATENT OFFICE.

THORP HELLAWELL, OF PATERSON, NEW JERSEY, ASSIGNOR TO HELLAWELL WARPING & WINDING COMPANY, OF PATERSON, NEW JERSEY, A CORPORATION OF NEW JERSEY.

FEED-CARRIAGE FOR WARPING-FRAMES.

1,321,631.

Specification of Letters Patent.

Patented Nov. 11, 1919.

Application filed January 12, 1917. Serial No. 141,957.

To all whom it may concern:

Be it known that I, THORP HELLAWELL, a citizen of the United States, and a resident of Paterson, in the county of Passaic 5 and State of New Jersey, have invented a new and Improved Feed - Carriage for Warping-Frames, of which the following is a full, clear, and exact description.

Among the principal objects which the 10 present invention has in view are: to provide means for delivering threads uniformly to a reel preparatory to the transfer therefrom of said threads to form warp drums for looms; to secure an even deposit of said 15 threads on said reel; to provide means for facilitating the repair of threads when being so delivered to the reel; to furnish a "cross" for disposing the threads in the desired parallel arrangement; to permit the 20 use of reeds of various dimensions; and to regulate the spread of the reel section on entrance to and departure from the carriage.

Drawings.

25 Figure 1 is a longitudinal vertical section of a carriage constructed and arranged in accordance with the present invention, and showing by broken lines, the positions in 30 which the guiding members of said carriage may be disposed;

Fig. 2 is a detail view in vertical cross section of a reed and support therefor, the section being taken as on the line 2—2 in 35 Fig. 1;

Fig. 3 is a detail view on a diminished scale showing in cross section, guide fingers with which the carriage is provided, the section being taken as on the line 3—3 in Fig. 1.

Description.

40 As seen in the accompanying drawings, the thread A is delivered from suitable spools over a rest bar or receiving member 8 of the herein-described carriage. The carriage consists of a skeleton frame having sides 9 spaced apart in parallel relation. The sides 9 are structurally united by cross-braces 10 and by tie rods 11 and 12. The 45 rods 11 and 12, as shown best in Figs. 2 and 3 of the drawings, are each provided with a screw-thread operatively engaged by clamping nuts, 13 and 14, respectively, between 50 which are clamped in service, reed-holders 55 15 and fingers 16, respectively. Both of

these are laterally adjustable in opposite directions from each other. Said tie-rods are further provided with clamping nuts 17, which clamp rigidly the sides 9 to hold the same in structural relation.

60 The thread A travels over the carriage in the direction shown by the arrow a in Fig. 1 of the drawings. During its travel it is supported by the glass spreader bars 18 and 19, and rollers 20 and 21, the roller 21 being 65 the delivering member of the device. Between the bars 18 and 19, the alternate threads are separated, one set of said threads passing below the bar 18 and above the bar 19, and the other set of threads passing 70 above the bar 18 and below the bar 19. As shown best in Fig. 1 of the drawings, this forms what is known in the art as a "cross." The "cross" is employed as the most efficient means for properly spacing the threads 75 in their passage through the carriage for delivery over the roller 21 thereof.

75 It is found desirable in feeding the thread A to the reel from which it is re-wound to the loom drum, that the width of the sections delivered by each operation of the carriage to the reel should have a predetermined compactness, and, further, that the edges of the sections being delivered should be prevented from thinning out, which 80 would produce in the woven material what is known in the art as "shiners." It is to prevent this that I use the guide fingers 16.

85 The fingers 16 are held on the tie rod 12 between the clamping nuts 14, said nuts frictionally engaging the end of the fingers with sufficient force to prevent them being dragged by the thread A out of their upright active position. The engagement of the nuts 14 is not sufficient, however, to prevent the tilting of the fingers 16 so that the ends thereof may be disposed below the plane of the thread A. This forms a convenient means for replacing any stray thread which may have passed to the outside of 100 either one or another of the fingers 16. That is, if one or more threads do thus stray, the adjacent finger 16 is lowered or tilted to the position as shown in dotted lines in Fig. 1 of the drawings, and the stray threads 105 then moved over until held between said fingers 16, when the depressed finger is again raised.

110 As indicated, the thread A is introduced to the carriage and to the reed 22 thereof,

with a spread wider than the space between the fingers 16, which governs the delivery of the section of the thread being transferred to the reel.

- 5 As seen best in Fig. 2 of the drawings, the holders 15 may be spread to accommodate reeds of different widths. To this end they are adjustable to the proper places by simply running the adjacent nuts over, sliding the 10 holders to the new position and again tightening the nuts. These reeds are of conventional construction and are produced in commerce to different widths. Heretofore the practice has been to provide a carriage with 15 a reed of maximum width and when the section has been reduced, the center of the reed alone has been employed. As a result of this practice, the center of the reed has had constant wear while the lateral portions have 20 had relatively little wear. Consequently, the center of the reed is worn away necessitating the abandonment of the whole reed. This has proved of considerable loss to manufacturers.
- 25 In the present invention, where the holders 15 are adjustable and variable in their relative separation, a reed of a width corresponding with the width of the section may be employed. The result of this practice is 30 that the reeds are worn evenly throughout their spread. As shown by the dotted lines in Fig. 1 of the drawings, the holders 15 and reed 22 carried thereby may be rocked on the rod 11 to positions which facilitate the 35 operations of "crossing" and knotting the threads.

By carrying the thread A in the present invention above the rollers 20 and 21, the same is made accessible for manipulation by 40 the operator. It also serves an additional and valued purpose in quickly detecting any broken threads which may result from the operation of the warping machinery. Also, any adhesion which would result in the 45 twisting is quickly detected and readily corrected.

Claims.

1. A feed carriage, comprising a thread 50 receiving and a delivering member; a separating reed disposed adjacent the receiving member; and guide fingers tilttable into and out of the plane of the threads for regulating the width of the thread supply at the 55 edges as they are delivered from said carriage.

2. A feed carriage as characterized comprising a receiving member supporting a thread supply and spreading the strands thereof for forming a single layer; a 60 spreader bar for separating the strands of said supply and forming a plurality of separated layers, the strands forming said layers being alternated in the first-mentioned layer; and a strand-separating reed pivotally mounted for swinging between and beyond said receiving member and guide bar for providing adjacent tying spaces.

3. A feed carriage, comprising a separating reed adjacent the receiving end of said carriage; a plurality of tilttable fingers disposed adjacent the delivery end of said carriage for guiding the thread passing therefrom; and a plurality of spreading members, disposed in parallel relation intermediate said reed and said fingers for forming a cross in the thread passing over said passage and between said reed and said fingers for preventing adhesions between said threads after passing through said 80 reeds.

4. A feed carriage, comprising a plurality of reed holders, means comprising the support of said reed holders enabling slidable lateral adjustment of the reed holders in opposite directions with respect to each other, and means for securing said reed holders in adjusted position.

5. A feed carriage, comprising a pair of reed holders, and instrumentalities enabling 90 slidable adjustment thereof in opposite directions with respect to each other, permitting the insertion of reeds of various widths according to the width of the warp section then in use, also including means for fixing 95 said reed holders in the various adjustments.

6. A feed carriage, comprising in combination, a pair of reed holders capable of adjustment oppositely to each other, means constituting the support therefor, means co-operating with said support for retaining the holders in adjusted position, guide fingers for confining the warp sections and preventing the tinning of the edges after said sections leave the reed carried by said 105 holders, and means providing a support for the fingers including means for adjusting them to correspond with the adjustment of said reed holders, said fingers being depressible on said supporting means to restore 110 stray edge threads of the warp sections.

THORP HELLAWELL.
